UNITED STATES PATENT OFFICE.

ERICK CARLSON, OF CHICAGO, ILLINOIS.

ACTION FOR PNEUMATIC PIANO-PLAYERS.

No. 892,400.

Specification of Letters Patent.

Patented July 7, 1908.

Application filed February 18, 1907. Serial No. 357,908.

To all whom it may concern:

Be it known that I, ERICK CARLSON, a citizen of the United States, residing at Chicago, in the county of Cook, State of Illinois, have invented certain new and useful Improvements in Actions for Pneumatic Piano-Players; and I do hereby declare the following to be a full, clear, and exact description of the invention, such as will enable others skilled 10 in the art to which it appertains to make and use the same.

This invention relates to pneumatic actions for pneumatic piano players and the object of the invention is to provide a very simple 15 form of action which will act quickly both to strike and release the keys.

The further object of the invention is to provide means whereby the primaries will be relieved of any undue pressure, this object 20 being attained by providing a return duct from each primary for the escape of surplus air. The provision of this duct permits quick return of the primary after being actuated and consequently a quick release of 25 the key of the piano.

My pneumatic action is designed particularly for use in connection with detached piano players although it will be understood of course that it may be employed in a combined piano and player without departing 30 from the spirit of the invention.

In the accompanying drawings, Figure 1 is a rear elevation of a pneumatic action constructed in accordance with my invention, 35 Fig. 2 is an end elevation thereof, Fig. 3 is a front elevation but showing a portion of the casing broken away, Fig. 4 is a view in elevation of the rear of the pneumatic action with the rear wall of the casing partly broken 40 away, Fig. 5 is a detail vertical sectional view taken centrally through the action, and, Fig. 6 is a detail horizontal sectional view.

Referring more specifically to the drawings my invention is shown as comprising a vacuum 45 chest having front and back walls 10 and 11 respectively and the chest is closed on all sides. The rear wall of the chest has its forward face dished or recessed as at 12, wherever one of the pneumatic actions is to 50 be located and over each recess is stretched a diaphragm 13 which forms the primary pneumatic. For convenience sake only one of the pneumatic actions will be described as they are all of the same construction. An arm 14 55 has its lower end turned laterally as at 15 and engaged in a groove 16 formed in a block 17

which is secured to the said forward face of the rear wall of the chest. From its cranked portion 15 the arm 14 extends vertically across the diaphragm 13 and through a guide 18 60 which is secured upon a disk 19 upon the diaphragm 13. The upper end portion of the arm 14 is turned rearwardly as at 20 and screw threaded and engaged upon the said threaded portion of the arm forward of the 65 wall 11 is a disk valve 21 which serves to close at times an opening 22 formed through the said wall and through which opening the threaded portion 20 of the arm projects. A similar disk valve 23 is also engaged adjust- 70 ably upon the threaded portion 20 of the arm 14 and this valve, as in the case of the valve 21, also serves to close the opening 22.

Formed in the rear wall is a transversely extending passage way 24 which has communication with the interior of the chest as indicated at 25. The purpose of this passage way will presently be stated.

Leading into the chest through the rear wall thereof and having communication with 80 the recesses 12 therein are air ducts 26 which lead from the orifices in the usual tracker board for the purpose of admitting air to the primary pneumatics when the openings in the music sheet pass over the orifices in the 85 board. Now in order to prevent the accumulation of air in the primaries and to vent the same, a short duct 27 leads from each primary into the passage way 24 and, having a bore of slightly less diameter than the bore 90 in the duct 26, it permits the slow exhaust, or bleeding of air from the primary.

A number of passage-ways 28 are formed through the top of the chest and communicate one with each opening 22, and upon the 95 said top of the chest is arranged a series of operating pneumatics 29 which are in communication with the passage ways 28 and which carry the usual key operating jacks 30. An opening 31 is formed through one side of 100 the chest and serves as a means whereby the air may be exhausted.

The operation of my pneumatic action is as follows: It is to be understood of course that there is a vacuum normally maintained 105 within the chest. Now when air is admitted through one of the ducts 26 by the registration of one of the openings in the music sheet with the corresponding orifice in the tracker board, the corresponding primary pneumatic 110 will be operated to cause the valve 23 to close the opening 22 to the atmosphere and

open valve 21 to put the operating pneumatic 29 in communication with the chest by way of the said opening 22. This will result in the collapse of the operating pneumatic owing to the fact that there is a vacuum in the chest, thereby striking the corresponding piano key.

What is claimed is—

A pneumatic action of the class described comprising a vacuum chest, a primary arranged within the chest, an air duct communicating with the primary, an operating pneumatic arranged upon the chest, there being a passage way formed through that wall of the chest upon which the primary is located and a passage way formed through the said wall and establishing communication between the first mentioned passage way and the operating pneumatic, a lever mounted for rocking

movement upon the said wall of the chest 20 and within the chest and extending across the primary and connected with the diaphragm thereof, a valve-stem integrally connected with said lever and extending through the first mentioned passage way and outwardly of the chest, and valves adjustable upon said stem, one of said valves being located within the chest and the other outwardly of the same, there being a bleed duct in communication with the said primary and opening into the atmosphere.

In testimony whereof, I affix my signature, in presence of two witnesses.

ERICK CARLSON.
